UNITED STATES PATENT OFFICE.

JOSEPH BERGER, JR., OF UTICA, NEW YORK, ASSIGNOR TO UNION SPECIAL MACHINE COMPANY, OF UTICA, NEW YORK, A CORPORATION OF NEW YORK.

THREAD-CONTROLLING MECHANISM FOR SEWING-MACHINES.

1,381,160.

Specification of Letters Patent. Patented June 14, 1921.

Application filed December 30, 1916. Serial No. 139,825.

To all whom it may concern:

Be it known that I, JOSEPH BERGER, Jr., a citizen of the United States, residing at Utica, in the county of Oneida, State of New York, have invented certain new and useful Improvements in Thread-Controlling Mechanism for Sewing-Machines, of which the following is a description, reference being had to the accompanying drawing and 10 to the figures of reference marked thereon.

The invention relates to new and useful improvements in a thread controlling mechanism for sewing machines and more particularly to a mechanism for controlling 15 the needle threads in a multiple needle single looper stitching mechanism.

In a two needle machine having a single looper it is customary to set the needles so that the needle eye of the needle farthest 20 from the looper when said looper is retracted is lower than the eye of the other needle. In a three needle machine with a single looper the eye of the farthest needle is lower than the eye of the middle needle 25 and the eye of the needle nearest the looper, when retracted, is higher than the eye of the middle needle.

An object of the present invention is to 30 provide a thread controlling mechanism for a stitch forming mechanism of the above character, which thread controlling mechanism will supply the proper amount of thread for each needle depending upon the distance that the eye of the needle passes 35 beneath the material.

In the drawings which show by way of illustration one embodiment of the invention:—

Figure 1 is a side view of the upper part 40 of a sewing machine having my improved thread controlling mechanism applied thereto, the needles being at their extreme upper position.

Fig. 2 is a similar view, but with the 45 needles at their extreme lower position.

Fig. 3 is a plan view of the same.

Fig. 4 is a detached perspective view 50 showing the needle bar with a thread guide carried thereby, the thread guides carried by the needle lever and the stationary thread guide.

Fig. 5 is a transverse sectional view 55 through the needle lever about the overhanging arm showing the fixed thread guide and the movable thread guides coöperating there-

with when the needle lever is at the upper end of its stroke.

Fig. 6 is a similar view, but showing the needle lever at the lower end of its stroke.

Our improved thread controlling mechanism is especially adapted for a sewing machine having two or more needles with which a single looper coöperates. It is well understood that in this type of machine the needle eyes should be set so that the needle 60 farthest from the looper when retracted has its eye the lowest, the next needle has its eye a little higher and if three needles are used then the next needle, that is the one nearest the looper when retracted, has 65 its eye the highest. The purpose of this is to secure a proper timing between the point of the looper and the needles so that the looper will with certainty enter each needle 70 loop in turn. In other words, if the looper 75 is set so as to cross the needle just above its eye, then the eye of the second needle must be set a little lower in order to give time for the looper point to reach the needle after having entered the first needle loop 80 and likewise the third needle must be set still a little lower to give time for the point of the looper to reach the needle and cross the needle just above its eye. In a construction of this character it will be apparent 85 that the needle eyes of the several needles will move different distances below the material being stitched; therefore, if all three of the needles be given the same amount of slack thread and the parts timed so 90 that the middle needle properly coöperates with the looper in making a tight stitch, then the first needle which does not take so much slack thread would make a loose stitch, while the last needle; that is the needle 95 farthest from the looper point when the looper is retracted, will require so much thread as to either break the thread through the tension placed thereon with the downward movement of the needle eye, or cause 100 the thread to cut through the fabric through the excessive pull of the needle on the thread.

The present invention is directed particularly to a thread controlling mechanism 105 which supplies just the proper amount of thread to the three needles, and takes up the thread so that the stitches made by the respective needles will be of uniform tightness. This is accomplished by pulling a lit- 110

tle more thread from the supply for the needle which is farthest from the looper when retracted, than is pulled from the supply for the other needles and it is further 5 accomplished by taking up a little more of the needle thread in the needle which is nearest the looper when retracted than is taken up for the other needles. In other words, the thread controlling mechanism 10 may be properly adjusted or set for forming a stitch of desired tightness with the middle needle, and auxiliary devices are used in conjunction therewith for causing the outer needles to form a stitch of similar 15 tightness and without injury to the threads or the fabric being stitched.

Referring more in detail to the drawings I have shown my invention as applied to a sewing machine having an overhanging arm 1 in 20 which a needle bar 2 reciprocates. The needle bar is reciprocated by a needle lever 3 which is connected to the needle bar by a link 4. The needle bar is provided with three needles 5, 6 and 7. These needles are set abreast, that 25 is, in a line substantially at right angles to the line of feed. Coöoperating with the three needles beneath the work support is a single looper 8. The mechanism for operating the looper may be of the usual character and has 30 not therefore been disclosed. The work support is indicated at 9 in the drawings. The eye 10 of the needle 5 is set at a lower point than the eye 11 of the needle 6 and the eye 11 of the needle 6 is also at a lower 35 point than the eye 12 of the needle 7. In other words, the eyes of the needles are in a line which is inclined to the longitudinal axis of the needle bar. The purpose of this has been referred to above, that is, to enable 40 the point of the looper 8 to cross each needle in turn at a point just above the eye of the needle so that the looper will with certainty engage each of the needle loops one after the other. It will be noted that when 45 the eyes of the needles are set, as above stated, that the eye of the needle 5 will move a greater distance beneath the work support 9 than the eye of needle 6 and the eye of the needle 7. When the needle 50 eye moves beneath the work support the previous loops shed from the looper are drawn up and the stitch set. In order to accomplish this the threads must be drawn taut by this downward movement of the eye 55 of the needle. If uniform stitches, therefore, are to be made by each needle, the needle 5 must have a little more thread given to it than the needle 6 and the needle 7 have a little less thread given to it than 60 to the needle 6.

The thread for the needle 5 is indicated at 5^a, the thread for the needle 6 is indicated at 6^a and the thread for the needle 7 is indicated at 7^a. The threads are led from the 65 supply through suitable tensions T which

are mounted on a bracket 13. From the tensions the threads are led through thread guides 14, thence between clamping disks 15, there being a pair of clamping disks for each thread, and thence through thread 70 guides 16. From the thread guides 16 the threads are led through thread eyes in an arm 17 which is fixed to the overhanging arm 1 of the machine. The arm 17 is carried by a shank 18 which extends into a socket 19 formed in the overhanging arm and said shank is secured in place by a set screw 20. The arm 17 is inclined downwardly toward its outer end and is formed with three spaced thread eyes 21, 22 and 23. The 75 thread 5^a passes through the thread eye 21; the thread 6^a passes through the thread eye 22 and the thread 7^a passes through the thread eye 23. From these thread eyes the thread passes through suitable eyes in an 80 arm 24 carried by the needle lever and thence through thread eyes in an arm 25 carried by the needle lever. The arm 25 has a thread eye 26 for the thread 5^a, an eye 27 for the thread 6^a and an eye 28 for the thread 7^a. 85 These thread eyes are arranged at different heights, as clearly shown in Figs. 1, 2 and 4 of the drawings. The needle threads, after passing through the thread eyes in the arm 25, are led through thread eyes in an arm 29 carried at the upper end of the needle bar and thence suitable eyes in the needle supporting collar 30 and thence through the eyes of the needles. An arm 31 90 is fixed to the needle lever and moves up and down therewith. The upper end of this arm is bent and positioned so as to engage the needle thread 5^a only. Said arm 31, when the needle lever moves downwardly, moves away from a line passing through the 95 thread guides 14 and the tension devices; and, consequently, on the downward movement of the needle lever this arm will pull the thread 5^a through its tension from the supply. The thread clamping disks may be 100 of any desired character, and, in fact, may be omitted from the machine, if desired, and, therefore, they have not been described in detail.

An arm 32, carried by the overhanging 105 arm of the machine, is disposed so as to engage the needle thread 7^a only on the downward movement of the needle lever. The thread eyes in the arm 29 carried by the needle bar move below this arm 32 and 110 said arm will therefore serve as a means for taking up some of the needle thread 7^a and this insures the needle 7 forming a tight stitch. The thread eyes 26, 27 and 28 are set, as above noted, at different heights. As 115 a consequence the eye 26 will take up less thread than the eye 27, while the eye 27 takes up less thread than the eye 28. The thread 5^a passes through the eye 26 and, therefore, this thread eye will take up less slack from 120 125 130

the needle thread of the needle 5 and consequently said needle 5 will have more thread given to it on its downward movement than the needle 6.

5 The arm 17, as above noted, extends downwardly. The thread 5^a passes through the eye 21, while the thread 6^a passes through the eye 22 and the thread 7^a passes through the eye 23. When the needle bar moves upwardly the arm 24, with its thread eyes, moves to a certain distance above the arm 17; therefore, thread will be at this time pulled through the thread clamping disks and from the supply. Inasmuch as the arm 15 24 moves a greater distance above the thread eye 21 than above the thread eye 22 more thread will be pulled off for the needle 5 than is pulled off for the needle 6, and less thread will be pulled off for the needle 7 than is pulled off for the needle 6. The arm 31, as above noted, also pulls on the thread 5^a, pulling slack from the supply and these combined features result in giving ample thread to the needle 5 on its downward movement so as to prevent the needle from placing the thread under such great strain as to cut the fabric, or cause the thread to break. These devices also coöperate in giving less thread to the needle 7 than is given 25 to the needle 6, which results in the needle 7 forming a tight stitch, and the stitches of all the needles being uniform. It is understood, of course, that the thread pulled off by the arm 24 moving above the thread eyes 30 in the arm 17 is given up to the needles on the downward movement of the needle lever and at the time when the needles are reaching the lower end of their stroke. The thread arm 17 is adjustable vertically and this 35

changes the position of the thread eyes 21, 40 22 and 23 and thus varies the amount of thread drawn off for the respective needles.

It is obvious that minor changes in the details of construction and the arrangement of parts may be made without departing 45 from the spirit of the invention as set forth in the appended claims.

Having thus described my invention what I claim as new and desire to secure by Letters Patent is:—

1. The combination of a needle bar, a plurality of needles carried thereby, a needle lever, thread eyes carried by the needle lever, a fixed thread arm having thread eyes for the needle threads, said arm being inclined to the plane of the needle lever whereby the movable thread eyes carried by the needle lever will pull off and give up different amounts in the respective threads. 55

2. The combination of a needle bar, a plurality of needles carried thereby, a needle lever, thread eyes carried by the needle lever, a fixed thread arm having thread eyes for the needle threads, said arm being inclined to the plane of the needle lever whereby the movable thread eyes carried by the needle lever will pull off and give up different amounts in the respective threads, said fixed thread arm being adjustable for varying the amount of thread pulled off and given up. 60 65 70

In testimony whereof I affix my signature in the presence of two witnesses.
